ATTACHMENT FOR PAPER-CUTTING MACHINES

John R. Brougher, Calvert, Tex.

Application August 30, 1944, Serial No. 551,872

1 Claim. (Cl. 164—94)

This invention relates to an attachment for a paper cutting machine whereby a machine of that type can be utilized for performing various operations for which separate machines heretofore have been necessary. For example, it becomes possible to convert a paper cutting machine quickly into a machine for punching holes through paper, for rounding the corners of sheets, etc.

A further object of the invention is to provide an attachment which can be quickly and securely placed in position for the purpose of converting the paper cutting machine to a paper punch or the like.

With the foregoing and other objects in view which will appear as the description proceeds, the invention consists of certain novel steps in the method and certain details of construction and combinations of parts hereinafter more fully described and pointed out in the claim, it being understood that changes may be made in the method disclosed and in the construction and arrangement of parts without departing from the spirit of the invention as claimed.

In the accompanying drawing the preferred form of the invention has been shown.

In said drawing:

Figure 1 is a perspective view partly in section showing the present improvements combined with a portion of a paper cutting machine of the "Diamond" type such as manufactured by Barnhart Brothers and Spindler, and in general use in printing establishments.

Figure 2 is an enlarged view of the present improvements, partly in section and partly in elevation.

In paper cutting machines of the type mentioned there is provided, in connection with the bed of the machine, an adjustable back gauge, a side gauge, a clamping bar, and a cutter bar. The cutter bar cooperates with a cutter stick which is removably mounted in a groove formed in the bed of the machine. In the cutting operation the stack of paper to be cut is placed against the side and back gauges after they have been properly adjusted, after which the clamping bar is lowered on to the paper. The cutter bar is then set in motion and moves downwardly through the paper to the cutter stick, thereby severing the paper.

Heretofore the foregoing operation is the only one which has been performed by a paper cutting machine and whenever it has been desired to punch holes in paper, to round the corners, to drill paper or perform other like operations, it

has been necessary to invest considerable money for the purpose of purchasing machines designed to perform these particular operations. This has been prohibitive in small printing establishments and, consequently, the operations of such establishments have been limited.

As before indicated the present invention is designed to enable the owner of a paper cutting machine to convert it so that it can be used for other purposes, such as punching holes, rounding corners, etc. The invention includes an attachment to be placed in the cutter stick groove after the cutter stick has been removed, so that the attachment is in position for actuation by the paper clamp ordinarily found on the machine. In the drawing a portion of the bed of the machine has been indicated at A. A back gauge is adjustably mounted on the bed and a portion thereof has been indicated at B. The paper clamp remains unchanged and is operated in the usual way. A portion of the clamp, which is suspended above the cutter stick groove C, has been indicated at D.

In the present case the attachment includes a block 1 proportioned to fit snugly but movably within the groove C and having a slot 2 extended thereto with its bottom wall flush with the top of bed A, this slot being sufficiently high to receive the work to be cut or punched. Those sides of the block nearest the walls of groove C are recessed, as at 3, to receive clamping jaws or plates 4 mounted on the respective ends of an adjusting screw 5, the middle portion of which is rotatably mounted in a forked ear 6 extended from one wall of the block 1 and located in groove C below the level of slot 2. A collar 7 is secured to the screw and is located in the forked ear 6, and this collar can be provided with one or more recesses 8 adapted to receive a pin or the like used for rotating the screw. The threads at one end of the screw are pitched oppositely to the threads of the other end of the screw and the two jaws are engaged by the respective ends of this screw. Thus when the screw is rotated in one direction, the jaws will be moved apart and can be forced into clamping or frictional engagement with the opposed walls of the groove C, whereas by reversing the rotation of the screw, the jaws can be drawn toward each other.

The upper portion of the block carries the element or elements to be used in punching or cutting the paper. In the present case a punch 9 is slidably mounted in the block and is held normally above the groove 2 by coiled spring 10. Any suitable means can be employed for limiting

the upward movement of the punch. For example, and as shown, the lower portion of the punch can be tapered upwardly and the opening in which the punch is mounted can be correspondingly tapered for a portion of its length.

It is to be understood that an attachment such as herein described can be provided for each type of operation to be performed. If a single hole is to be punched through a stack of paper, the attachment will be provided with a single punch as shown. If two holes or more are to be punched, two or more of the yieldingly supported elements 9 can be used in the block. If the attachment is to be employed for rounding corners, the reciprocating element could be in the form of a curved knife mounted for sliding movement in the block. Thus, the owner of a paper cutting machine can be equipped with several attachments each adapted to perform a particular operation. When it is desired to use one of the attachments the jaws 4 are drawn toward each other by rotating screw 5 in one direction. The attachment is then placed in the groove C after the cutter stick has been removed and is at that time directly beneath the clamp D ordinarily used on a paper cutting machine. The attachment is not fastened in place until after it has been properly located with respect to the guides. After it has been correctly positioned, the attachment is secured by rotating screw 5 so as to force the jaws 4 outwardly against the walls of the groove C. Thereafter the material to be perforated is placed on the bed against the

gauges and with a portion in the slot 2. The clamp D is then lowered in the usual way and will descend upon the upper end of the punch 8, forcing it downwardly through the material. By 5 raising the clamp the punch will be lifted by its spring and the operation then can be repeated.

By the term "punch" it is to be understood that reference is made to any kind of cutting or paper processing tool mounted for reciprocation 10 in the slot.

Furthermore, while one expandible attachment only has been shown in position within the groove C, it is to be understood that two or more of these expandible clamping devices suitably connected could be used for supporting any selected type of paper processing element.

What is claimed is:

The combination with the bed and movable paper clamps of a paper cutting machine, there being a cutter-stick groove in the bed beneath the clamp, of an attachment removably seated in the groove and including a block having a slot for the reception of material to be cut, jaws movably mounted at the sides of the block and within the groove, means carried by the block for adjustably connecting the jaws to the block, said jaws being mounted for movement away from each other to frictionally engage the walls of the groove, and a yieldingly supported paper cutting 25 element carried by the block and positioned for actuation by the clamp.

JOHN R. BROUGHER.
